OF CINCINNATI, OHIO, A CORPORATION OF OHIO

CONTAINER SEALING MACHINE

Application filed March 30, 1931. Serial No. 526,445.

My invention relates to container sealing machines, particularly of the conveyor pressure belt type.

In the sealing of containers it has been customary in the past to apply an adhesive, such as silicate of soda or glue, to the closure flaps of containers, and to then pass the containers between pressure belts in which the closure flaps are firmly pressed into sealing position and held in such position sufficient time for a good tight bond to occur.

Machines of this type are old and well known in the art, and it has further been customary to provide resilient mounting for one or the other of the pressure belts, so that slight irregularities in the container seal will be compensated for.

To the best of my knowledge and belief, however, no sealing machine of this type has ever been provided, in which containers of substantially unequal size or dimensions could be accommodated.

It is the object of my invention to provide a container sealer in which the closure flaps of containers of widely variant dimensions can be accommodated without the necessity of adjustment of the machine for size. In order to explain clearly what I mean by containers of substantially unequal dimensions, I may state that my sealing machine is adapted to seal in succession containers, for example, twelve inches in height followed by containers sixteen inches in height.

Another object of my invention is the provision of a sealing machine in which automatically adjustable belt tightening means is provided.

Another object of my invention is the provision of a sealing machine in which stops are arranged to prevent the supports for the pressure belt which accommodates itself to the widely variant sizes of successive containers, from becoming wedged in such position as might crush some of the containers being sealed.

Referring to the drawing:

Figure 1 is a side elevation of a typical installation of my invention.

Figure 2 is a detail sectional view taken along the lines 2-2 in Figure 1.

I have shown in the modification illustrated, a sealing machine having upright pedestals 1 provided with suitable supporting bases.

2. The lower conveyor is supported on said frame members 3, having tubular bosses 4 which slidably engage the pedestals 1. The tubular bosses which extend from the said frame members 3 are provided with adjustment bolts 5 which may be employed to mount the said frame members at a desired position on the pedestals.

An electric motor 6 is coupled to a suitable reduction gear unit 7. The reduction gear unit has a pulley 8 which is connected by a belt 9 to a driven pulley 10. On the shaft 11 of the pulley 10 there is a pinion 12 which meshes with a gear 13 which is fixed on a shaft 14. The shaft 14 has a pulley or roll 15 mounted on it, over which the conveyor belt 16 passes in a continuous formation.

So that the motor and reduction gear unit may be readily adjustable with the frame members 3, I have employed straps 17 which are secured to the frame members 3, and which support the base 18 on which the motor 6 and reduction gear unit 7 are mounted. Supporting the belt conveyor 16 are a series of rollers 19 which have spindles 20 journaled in journal bearings 20a.

In the usual manner, the conveyor belt 16 passes over a pulley 21 which has a spindle 22 mounted in adjustable lugs 23. This provides a ready adjustment for the conveyor belt 16.

The shaft 14 carries a beveled gear 24 which engages a beveled gear 25 mounted on an upright shaft 26. The shaft 26 carries another beveled gear 27 which engages a beveled gear 28. The beveled gear 28 is mounted on the shaft 29 which extends across the frame of the machine and is journaled in the frame members 30 which, like the frame members 3, are adjustably mounted on the spindles, but by means of tubular bosses 31 and adjustment bolts 32. On the shaft 29 there is the pulley 33 over which the pressure belt 34 extends.

At the other end of the machine there is a pulley 35 over which the belt 34 extends. The pulley 35 has a shaft 36 mounted in ad-

justable bearing blocks 37. Shaft 38 extend across between the frame members 30 and carry tubular bosses 39 of roller supporting arms 40. Extending across between the 5 bosses 41 of the arms 40 are the spindles 42 of the rollers 43 which bear down against the belt 34.

It will be noted that the pressure belt 34 extends about rollers 44, and then up over 10 rollers 45 journaled in slideable blocks 46. Weights 47 secured by cables 48 which extend over pulleys 49, exert a pull upwardly on the blocks 46. The size of the weights 47 will be such that immediately upon any 15 slackness in the pressure belt 34, the idler pulleys 45 will take up the slackness in the belt.

To prevent the supporting arms 40 and 20 rollers 43 from becoming wedged in a position where they will not give in line with the direction of movement of the containers through the machine, which direction is indicated by the arrow between the containers 25 50 and 51, I have extended across between the frame members 30 bars 52, which the arms 40 will strike against before they can be moved to a position inclined to the right, as shown in Figure 1, from a line extending 30 vertically down from the axis of the shafts 38.

The operation of the sealing machine will be obvious. The containers are fed in between the belts 34 and 16, and, as indicated, 35 containers of widely variant dimensions, such as the container indicated at 50 and the container indicated at 51, will be accommodated between the pressure belts. While it is customary to pre-seal the bottom closure 40 flaps of the container prior to inserting the contents into them, the machine is adapted for sealing and pressing both upper and lower closure flaps during the same operation.

Having thus described my invention, what 45 I claim as new and desire to secure by Letters Patent, is:—

1. A sealing machine for containers having cooperating conveying and pressing belts, one of which is movable in substantially a fixed plane, and the other of which engages rollers which are supported on hinged frames which yield to permit the conveying belt to accommodate containers of substantially different dimensions, said rollers being of relatively small diameter and being spaced sufficiently closely so that a plurality of said rollers overlie each container during the sealing thereof.

2. A sealing machine for containers having cooperating conveying and pressing belts, one of which is movable in substantially a fixed plane, and the other of which engages rollers which are supported on hinged frames which yield to permit the conveying belt to accommodate containers of substan-

tially different dimensions, said rollers being of relatively small diameter and being spaced sufficiently closely so that a plurality of said rollers overlie each container during the sealing thereof, said machine having stops to prevent said frames being inclined in a direction counter to the movement of containers through said machine. 70

3. A sealing machine for containers having cooperating conveying and pressing belts, one of which is movable in substantially a fixed plane, and the other of which engages rollers which are supported on hinged frames which yield to permit the conveying belt to accommodate containers of substantially different dimensions, said rollers being of relatively small diameter and being spaced sufficiently closely so that a plurality of said rollers overlie each container during the sealing thereof, said belts being carried on 75 members extending longitudinally of the machine, which members are vertically adjustable. 80

4. A sealing machine having a belt conveyor on which containers to be sealed will be carried, and a pressure belt having mounting means yieldable in the direction of movement of said conveyor, said mounting means comprising a series of rollers mounted independently on pivoted arms, said rollers being of relatively small diameter and being spaced sufficiently closely so that a plurality of said rollers overlie each container during the sealing thereof. 90

5. A sealing machine having a belt conveyor on which containers to be sealed will be carried, and a pressure belt having mounting means yieldable in the direction of movement of said conveyor, said mounting means comprising a series of rollers mounted independently on pivoted arms, said rollers being of relatively small diameter and being spaced sufficiently closely so that a plurality of said rollers overlie each container during the sealing thereof, said machine being provided with stops to prevent the inclination of said arms counter to the direction of movement of said conveyor. 100

6. A sealing machine having a belt conveyor on which containers to be sealed will be carried, and a pressure belt having mounting means yieldable in the direction of movement of said conveyor, said mounting means comprising a series of rollers mounted independently on pivoted arms, said rollers being of relatively small diameter and being spaced sufficiently closely so that a plurality of said rollers overlie each container during the sealing thereof, said arms being supported on 110 vertically adjustable frame members. 120

7. A sealing machine for containers having cooperating conveying and pressing belts, one of which is movable in substantially a fixed plane, and the other of which en- 130

gages rollers which are supported on hinged frames which yield to permit the conveying belt to accommodate containers of substantially different dimensions, said rollers being 5 of relatively small diameter and being spaced sufficiently closely so that a plurality of said rollers overlie each container during the sealing thereof, said belts being carried on members extending longitudinally of the machine, which members are vertically adjustable, said members carrying said belt movable in a fixed plane also carrying a motor for driving said belts.

8. A sealing machine for containers having 15 cooperating conveying and pressing belts, one of which is movable in substantially a fixed plane, and the other of which engages rollers which are supported on hinged frames which yield to permit the conveying belt to accommodate containers of substantially different dimensions, said rollers being 20 of relatively small diameter and being spaced sufficiently closely so that a plurality of said rollers overlie each container during the sealing thereof, said belts being carried on members extending longitudinally of the machine, which members are vertically adjustable, said members carrying said belt movable 25 in a fixed plane also carrying a motor for driving said belts, and a reduction gear unit 30 also carried by said last noted members.
